AUGUST P. JURGENSEN:
BY
Wiederholt Fairbanks
ATTORNEYS.

UNITED STATES PATENT OFFICE

AUGUST P. JURGENSEN, OF PHILADELPHIA, PENNSYLVANIA, ASSIGNOR TO CONCENTRIC AIR CELLS AUTOMATIC COMPANY, OF PHILADELPHIA, PENNSYLVANIA, A CORPORATION OF DELAWARE

AIR-CELL PIPE COVERING

Original application filed January 30, 1929, Serial No. 336,163. Divided and this application filed July 23, 1929. Serial No. 380,445.

My invention relates to a new and useful air cell pipe covering for insulating steam pipes, flues, exhaust pipes and the like, and it relates to a novel air cell-pipe covering which is inexpensive to produce, which is of a relatively great cross-sectional strength, and one which is of a uniform cross-sectional thickness throughout, this application being a division of my copending application Serial

10 No. 336,163, filed January 30, 1928.

Air-cell pipe coverings heretofore made have generally consisted of a spiral cylindrical construction formed of a spirally wound or rolled continuous sheet of heat resisting material, which was difficult and costly to make and which had inner and outer laps or joints, at the inner and outer ends of the spirally wound or rolled sheet. Furthermore, air-cell pipe coverings heretofore made have consisted of a continuous or integral spirally formed cylinder which was cut axially or longitudinally after formation or completion to permit insertion thereinto, of the pipe to be insulated or covered.

25 A still further disadvantage resided in the fact that a spirally formed air cell pipe covering was not of a uniform diameter or cross section, with a resulting inaccuracy in the fit of said air cell pipe covering to the heating pipe to be insulated and covered thereby.

It is therefore the object of my invention to produce a novel air cell pipe covering which is of uniform diameter and cross sectional thickness, and one which is formed initially axially split, with the edges thereof

35 flush, contiguous, juxtaposed and in the same cylindrical plane, thereby eliminating the objectionable laps and joints resulting from spiral formations above referred to.

To the above ends my novel air cell pipe covering consists of a plurality of sheets of heat resisting material of the same length but of gradually decreasing widths, with the

45 widest of said sheets forming the outer circumference and the narrowest of said sheets forming the inner circumference, said sheets being coated with an adhesive and moulded together in concentric nested formation with the longitudinal edges of said sheets, par-

allel, contiguous, and in the same cylindrical plane.

My novel air cell pipe covering further possesses other features of construction and advantage which will be hereinafter described and claimed.

For the purpose of illustrating my invention I have shown in the accompanying drawings forms thereof which are at present preferred by me although it is to be understood that the same are only illustrative of the nature of my invention and that my invention is not limited to the precise construction shown and described.

In the accompanying drawings:—

Figure 1, represents a perspective view of a composite blank form of a plurality of sheets of corrugated heat resisting material and an inner canvas cover sheet from which my novel air-cell covering is formed.

Figure 2, represents a perspective view of a sheet of corrugated heat resisting material shown coated with a heat resisting adhesive.

Figure 3, represents a fragmentary vertical sectional view illustrating the manner of moulding the composite blank shown in Figure 1.

Figure 4, represents a perspective view of the air cell pipe covering formed by moulding the blank shown in Fig. 1 by the mechanism shown in Fig. 3.

Figure 5, represents a pair of the semi-cylindrical sections shown in Figure 4 assembled to form a complete cylindrical air cell pipe covering.

Figure 6, represents a cross sectional view of a modified form of my novel air cell pipe covering.

Figures 7 and 8 illustrate the means and the steps for forming the air pipe covering shown in Figure 6.

Referring to the drawings, in which like reference characters indicate like parts, my novel air cell pipe covering of a composite blank composed of a plurality of sheets, 1, 2, 3 and 4 of corrugated or plain heat resisting material, such as asbestos or the like, all of the same length, but of gradually decreasing width, with the widest sheet 1 at the bottom to form the outside circumference and

the narrowest sheet 4 at the top to form the inner circumference of the semi-cylindrical product when moulded. The sheets 1 to 4 are coated with an adhesive 5 to form a unitary composite blank which is provided with the top cover layer 6 of canvas or the like, which is of the same length and width as the bottom sheet 1. The composite blank formed of the sheets 1 to 4 and 6 superimposed in the order shown is fed into the mould 7 which is carried by the rods 8 carrying the rollers 9 riding on the cams 10 fast on the shaft 11. The sheets 1 to 4 and 6 forming the composite blank are clamped against the mould or core 12 on the core block 13 which is carried by the shaft 14 and secured in any desired position by the nut 15, by means of the plunger 16 carried by the rod 17 which carries the roller 18 riding on the cam 19 fast on the shaft 11, which is actuated by any suitable means not shown. The moulds 7 are then raised into the position shown in the right hand side portion of Figure 3 to mould the sheets 1 to 4 and 6 into the semi-cylindrical section 20 shown in Figure 4.

By making the sheets 1 to 4 of gradually and proportionally decreasing widths, I produce a semi-cylindrical section 20 having the flat edges 21 which are composed of the longitudinal edges of the sheets 1 to 4 which are flush, parallel and in the same horizontal and cylindrical plane, with the uppermost sheet 4 forming the inner circumference and the lowermost sheet 1 forming the outer circumference of the section. The top cover layer 6 forms a lining for the inner surface of the semi-cylindrical section 20 and a binder for the edges 21 thereof. Two of the sections 20 are clamped around a pipe to be insulated in the manner illustrated in Figure 5.

In the right hand portion of Figure 3 I have illustrated the use of a composite blank formed of two sheets of corrugated paper 1 and 2 in lieu of the four shown in Figure 1, and I have shown the moulds 7 in the closed position clamped against the mould or core 22 of the core block 13.

It is to be understood that plain or corrugated paper may be used and that a composite blank formed of any number of sheets may be employed. It is further to be noted that the cover layer 6 may be duplicated on the outside of the semi-cylindrical section 20 or may be entirely dispensed with if desired.

In Figure 6 I have shown a modified form of my novel air cell pipe covering 23 which consists of the sheets 24, 25, 26 and 27, with or without the cover layer 6, all of the same length but of gradually decreasing widths, coated with an adhesive 5 and arranged on a mould 28 carried by the plunger 29 which clamps the pyramidal arranged sheets 24 to 27 against the core or mandrel 30 (see Figure 7) the mould 28 being then closed (see Figure 8) by the rollers 31 on the rods 32 which are

actuated by cams similar to those shown in Figure 3, to form the cylindrical air cell pipe covering 23 shown in Figure 6. The cylindrical covering (in lieu of the sectional semi-cylindrical air pipe covering 20) is split at 70 34 with the edges of the sheets 24 to 27 juxtaposed, flush, and in the same cylindrical plane, and the product thus obtained is perfectly cylindrical and has a uniform cross sectional thickness throughout. 75

It will thus be seen that I have produced a novel air cell pipe covering which is formed initially split or in semi-cylindrical sections, and the edges of which are parallel, juxtaposed and in the same cylindrical plane, so that my novel air cell pipe covering is entirely free from the laps and joints due to the spiral formation resulting from the winding of a continuous sheet around a mandrel which prevents perfect roundness and uniformity of cross sectional thickness. 80

It is further to be noted that my novel air cell pipe covering is inexpensive to produce since the moulding of several sheets cut to the predetermined size is an easier and quicker operation than the winding of a continuous sheet about a mandrel and it gives more accurate and efficient results. 90

By producing an initially split air cell pipe covering, whether of the variety shown in Figure 4 or in Figure 6, I eliminate the operation of cutting a continuously formed spiral air cell pipe covering after it is formed thus effecting a saving in labor. The inner canvas cover or lining layer 6 also forms a 95 binder for the juxtaposed edges of the sheets 1 to 4 forming the edges 21 of the semi-cylindrical section 20 thereby imparting a neat appearance and greatly adding to the strength of my novel product. 100

I am aware that the invention may be embodied in other specific forms without departing from the spirit or essential attributes thereof, and I therefore desire the present embodiment to be considered in all respects 110 as illustrative and not restrictive, reference being had to the appended claims rather than to the foregoing description to indicate the scope of the invention. 105

Having thus described my invention, what I claim as new, and desire to secure by Letters Patent, is:—

1. A composite blank for forming concentric air-cell pipe covering composed of a plurality of superimposed cemented sheets of heat insulating material of the same length but of gradually decreasing widths, with the widest of said sheets at the bottom and the narrowest of said sheets at the top, and a top cover sheet of approximately the same length and width as the widest of said sheets. 125

2. An air-cell pipe covering composed of a plurality of superimposed sheets of heat resisting material of the same length but of gradually decreasing widths with the widest 130

of said sheets at the bottom and the narrowest of said sheets at the top, and a top cover sheet of approximately the same length and width as the lowermost of said sheets, said sheets being cemented and moulded in concentric relation to each other.

3. As a new article of manufacture, an air-cell pipe covering formed of a plurality of pyramidal superimposed sheets of heat insulating material of the same length but of gradually decreasing widths, said sheets being superimposed with the widest sheet at the bottom and the narrowest sheet on top and cemented and moulded in concentric relation to each other to form a longitudinally split covering of cylindrical formation and of uniform cross section with the juxtaposed longitudinal edges of said sheets in the same plane.
